UNITED STATES PATENT OFFICE.

GEORGE W. MCGILL, OF RIVERDALE, NEW YORK.

FASTENER FOR ENVELOPES.

SPECIFICATION forming part of Letters Patent No. 414,071, dated October 29, 1889.

Application filed June 22, 1889. Serial No. 315,174. (No model.)

To all whom it may concern:

Be it known that I, GEORGE W. MCGILL, a citizen of the United States, residing at Riverdale, in the county of New York and State 5 of New York, have invented new and useful Improvements in Fasteners for Envelopes and for other Purposes, of which the following is a specification.

In transmitting samples by mail in un-10 sealed envelopes or similar wrappers it is very desirable to provide means whereby the closing-flap can be securely held in its closed position by contrivances that will permit it to be released with ease and facility that the 15 officials may inspect the inclosures and then quickly and conveniently reclose and secure the envelopes or packages.

The object of my invention is to provide a novel, simple, efficient, and economical de-20 vice for accomplishing the purposes mentioned, and which is also capable of being otherwise used—as, for instance, to fasten or bind together two different sets of papers or documents to permit one set to be removed 25 without disturbing that part of the fastener which secures the other set.

The invention consists in the novel features of construction hereinafter described and claimed, reference being made to the ac-30 companying drawings, illustrating the invention, in which—

Figure 1 is a perspective view of a blank to form the fastener; Fig. 2, a similar view showing the blank folded upon itself longitudinally along its median line; Fig. 3, a similar view showing the inner member of the blank bent into two prongs; Fig. 4, a perspective view of the completed fastener; Fig. 5, a transverse sectional view of the fastener; Fig. 6, a sectional elevation showing the fastener applied to secure two thicknesses or different sets of papers; Fig. 7, a perspective view of a blank to form a modified form of fastener; Fig. 8, a similar view showing said blank folded upon itself longitudinally along its median line, and Fig. 9 a perspective view of the completed fastener formed according to the modification.

In order to enable those skilled in the art 50 to make and use my invention, I will now describe the same in detail, referring to the

drawings, where the blank is shown in Fig. 1, and is composed of two strips of metal 3 and 4, parallel with each other and one longer than the other, the center of both being integral 55 with each other, as by a neck 2, for a distance equal to the spread of the completed staple formed from the blank. To form the staple-fastener this blank is folded upon itself longitudinally along its median line, as in Fig. 60 2, and the extremities of the inner member 3 are bent outward to form two separated prongs 5, which are preferably pointed. The other or outer member 4 is folded around and toward the prongs 5 to constitute shoulders 65 6, and then bent outward into prongs 7, the inside surfaces of which preferably rest against and are parallel to the outer faces of the prongs 5. This construction provides a fastener wherein the head is composed of two 70 thicknesses or superposed layers, with the inner prongs between and next to the outer prongs, both pairs of prongs extending laterally in the same direction from the duplex head. The shoulders 6, by projecting longitudinally beyond the outer prongs 7, serve to cover and conceal the holes or slits made in the papers for the insertion of the prongs. The prongs which lie adjacent to or against 75 each other are made of different lengths to facilitate bending the prongs down upon the papers, and, as shown, the inside prongs 5 are the shortest, so that they can be passed through one thickness or set of papers, as at 8, Fig. 6, and be clinched down, and the outer 85 prongs 7 inserted through another thickness or set of papers, as at 9, and then clinched down in either direction.

In Fig. 9 the fastener also comprises a head of two thicknesses or members 3 and 4, and 90 is made from the blank, Fig. 7, by folding such blank upon itself longitudinally along its median line, as shown in Fig. 8, and then binding the extremities of the two members at right angles to the duplex head to form 95 the inner prongs 5 and outer prongs 7. In this modified construction the shoulders 6 (shown in Figs. 4 and 6) are omitted.

The fastener is composed of a single piece of material, and the blanks are preferably 100 stamped from any kind of sheet metal which will permit a blank to be easily bent or folded

into the form described and enable the prongs to be conveniently bent or clinched down to secure the papers.

The device is useful as a clasp for closing the flap of an envelope or other wrapper and for binding together two different sets of papers, as, before explained; but while the invention is especially adapted for the two purposes mentioned I do not confine myself thereto, as obviously the fastener can be variously used.

Having thus described my invention, what I claim is—

The duplex-pronged fastener herein de-

scribed, consisting of two pairs of prongs projecting in the same direction from one side of a head composed of two superposed layers formed integral and the prongs of each pair respectively in close parallel contact, each layer of the head carrying a pair of the prongs, substantially as described.

In testimony whereof I have affixed my signature in presence of two witnesses.

GEORGE W. MCGILL.
